MILLER REESE HUTCHISON, OF LLEWELLYN PARK, WEST ORANGE, NEW JERSEY, AS
SIGNOR, BY MESNE ASSIGNMENTS, TO ACOUSTIC PRODUCTS COMPANY, OF NEW
YORK, N. Y., A CORPORATION OF DELAWARE.

LOUD-SPEAKER.

Application filed March 20, 1926. Serial No. 98,763.

This invention relates to improvements in sound producing or sound reproducing instruments, usually referred to in the arts as loud speakers, and has for its objects to 5 improve the volume, quality and tone, as well as the truth of vocal and instrumental music and render it free from the customary confusions and distortions of sounds over instruments heretofore proposed or 10 constructed.

Through the widespread introduction of radio loud speakers of various kinds and types, much of course has been accomplished. Yet none of them faithfully reproduces true 15 tone quality, or combines full volume with faithfulness of the original sound of singer, instrument, band or orchestra, previous to my inventions.

By using a plurality of horns or other 20 suitable sounding devices as I herein indicate, I plan scientifically to utilize resonance rather than try to overcome resonance, as heretofore attempted in other loud speakers on the market. It is as impossible to expect 25 one diaphragm, or one diaphragm horn unit faithfully to reproduce all notes of the register as it is to expect one organ pipe so to function.

In a co-pending patent application, Serial 30 Number 87073, filed February 9th, 1926, loud speakers, I have set forth specifications, drawings and claims, covering a considerably more elaborate invention adapted for the concert hall and stage, and the present 35 invention concerns a modification of comparatively low cost for home use.

With the foregoing and other objects in view, the invention now described consists in the novel parts or arrangement of parts 40 constituting an improved loud speaker, and one adapted to superior radio reception for home installation, all as hereinafter will be more fully disclosed and particularly pointed out in the claims. Referring to the 45 accompanying drawings forming a part of this specification in which like numerals designate like parts in all the views:

Figure 1, is a front view of one design of one of my loud speakers partially in section.

Figure 2, is a side view of one of my instruments in elevation, turned ninety degrees to the right.

Figure 3, is a sectional view looking down

upon a cross cut along the dotted line 3—3, of Figure 1.

With further reference to Figure 1, 5, 6, 7, 8, 9, 10 and 11, are the throat outlets of seven resonating pipes or tubes 46, 47, 48, 49, 50, 51, three curving off to the left, and three curving off to the right of a central standard tube. The three pipes 47, 49 and 51, curve in a comparatively simple bend to the right, but the three pipes 46, 48 and 50, not only curve to the left, but are bent also into a compound curve, bending backward as well as to the left in order to increase their lengths. By this construction the pipe 47, is the shortest, measuring from the throat opening 6, to the common lower outlet or end 19, and the pipe 46 is consequently a little longer measuring from the throat opening 5, to the common lower outlet or end 19, by virtue of the longer compound bend in the said pipe 46. The next longer pipe is 49, measuring from the throat 8, to the common outlet or end 19 with its simple bend. The next longer pipe is 48, measuring from the throat 7 to the common outlet or end 19, with its double or compound bend. The next longer pipe is 51 measuring from the throat 10, to the common outlet or end 19, with its simple bend. The next longer pipe is 50, measuring from the throat 9, to the common outlet or end 19, with its double or compound bend. The next longer pipe is 52 with no bends. The common outlet lower end of all of these resonating pipes is seated in the socket or receptacle 20, and against the shoulder 21, thereof leading to the open throat 34.

The projecting socket 20, is an extension of the top of the casing 28. Within this casing is a diaphragm seating ring 29, of any suitable material, against which rests the diaphragm 30, held in position by the second diaphragm seating a supporting ring 31, all supported by the member 32, having a concave or inverted bell shaped contour 33, above the diaphragm and communicating with the throat outlet 34, common to all of the resonating horns. 35 and 36 are permanent magnets of hardened steel suitably charged with magnetism, and 39 and 40, are soft iron pole pieces wound with coils of insulated magnet wire, 42 and 43, the said pole pieces forming a magnetic circuit or

connection with the permanent magnets. 37 and 38 are the soft iron pole pieces or pole ends in close proximity to the diaphragm 30. 44 and 45, are binding posts 5 anchoring the ends of the coil windings in the usual way. This device is therefore a conventional telephone receiver, or sound propagator, or loud speaker unit, such as I employ in my previously described invention 10 and to which patent application I have given the aforesaid serial number.

With further reference to Figure 2. 12, 14, 16, 18 are the bell ends of the resonating pipes 46, 48, 50 and 52, visible from the side view, and 5, 7, 9, and 11 are the positions of the respective throat openings of the double compound bent resonating pipes. 20 is the supporting socket on top of the casing 28, containing the telephone receiver, or loud speaker unit, and 44 is one of the binding posts anchoring one end of the winding of the loud speaker coil, which coil is adapted for convenient and ready connection to a source of electrical current or energy having 25 speech, song, or instrumental music characteristics.

In my previously filed patent application referred to, I employ twelve horns or more of different resonating characteristics and 30 twelve or more telephone receivers, or loud speaker units with their individual diaphragms.

In my present patent application I employ a plurality of horns or sounding devices of 35 different resonance characteristics with a single diaphragm or a diaphragm common to all of the horns or sounding devices as a less elaborate and expensive compromise over my more scientifically complete twelve 40 horn and twelve diaphragm design.

In order to accomplish scientific and superior results with a single diaphragm, over instruments heretofore designed or constructed, I embody certain principles in the 45 science of musical sounds with a plurality of horns. In order to accomplish new results and approximate as a compromise performance with seven horns instead of twelve horns, the seven horns in the present instrument 50 are tuned to take advantage of all of the vibration characteristics of any single diaphragm. One diaphragm possesses a far greater flexibility and range of note and tone producing vibrations than any single 55 horn or sound projector. It has been repeatedly shown by experiment that different areas of one and the same diaphragm may simultaneously undergo different rates of vibration. When fine sand is strewn on a 60 vibrating diaphragm it may be observed that portions are moving up and down. There are certain lines toward which the sand gathers, indicating that these parts are relatively at rest; the lines on which the sand 65 accumulates are called nodal lines, and form

patterns and figures which are always the same for the same note, but differ for each change of pitch or quality. It is thus shown that a diaphragm vibrates in various subdivisions.

A horn is an air resonator, and operates through the enclosed air column. The horn reacts upon the diaphragm, causing it to have a period different from that which it had before the horn was applied. Therefore, when a horn is added to a diaphragm, the response is greatly altered. A long horn 70 seems to respond nearly as well to high tones as does a short one, while the response to low tones is much greater than is that of a short horn; the response below the fundamental of a horn is very feeble. A horn acts very much like the sounding box associated 75 with a tuning fork. They both serve a double purpose; to produce a louder sound, and to purify the tone by reinforcing only the fundamental. A horn itself cannot originate any component tone and hence cannot add anything to the composition of the sound. It can only take up the energy 80 of vibration of some generator, a diaphragm for example, and give it out in a different loudness. A diaphragm, as has been pointed out, may not only undergo different vibrations at different localities in 85 its area, but the whole diaphragm, if properly supported by pasteboard, cork or rubber rings, is free to be driven not only to its natural period, but by forced vibration into a great range of vibration periods, a 90 range far greater than the resonating air column of any horn.

A sound producing or sound projecting instrument, with one horn associated with 95 one diaphragm, is the worst of combinations since diaphragms respond with remarkable facility to tones of a wide range of pitch and to a great variety of tone combinations, whereas horns respond to sounds of particular quality only.

Two horns, each turned to a different 100 note, I found were an improvement when associated with a single diaphragm, yet theoretically and in my experimental work the single diaphragm exceeds the note and tone 105 flexibility of two horns, even when they are tuned to a middle register and are capable of resonating above and below their fundamental notes.

Three horns give superior results on one 110 diaphragm to two horns, and four horns give still better results than three horns, and I have found that I may to advantage operate as many as twelve horns upon a single or common diaphragm, but seven 115 horns give satisfactory results.

With seven horns of different resonance 120 periods or different musical characteristics associated with a single or common diaphragm, I am enabled for the first time to 125

- utilize and project with great volume, truth and beauty the numerous and complex natural and forced diaphragm vibrations. Not only do I give volume to and reinforce the natural vibrations of a diaphragm supported between suitable rings to allow for elasticity and freedom of movement, but I utilize important vibrations localized at various points in the area of the diaphragm.
- 10 Again through my plurality of horns, each of a different musical characteristic and associated with a single or common diaphragm, I do not dampen or modify the free inherent qualities of the diaphragm.
- 15 In fact my horns of different characteristics with their common throat, when the said common throat is in communication with a single elastically supported diaphragm, allow said diaphragm to vibrate substantially
- 20 as it would vibrate without the association of any horn at all, and at the same time reinforcing all of the notes, tones and overtones generated in the diaphragm.
- Having described my invention, I claim:—
1. A radio receiver comprising a casing, a diaphragm, a shallow cup-shaped front cover with throat opening therein, means for actuating said diaphragm, and a plurality of sounding devices, each sounding device having a resonating tube of different length to tune said tube to a single but different fundamental note.
2. A musical instrument comprising a support having a sound responsive element
- therein, a central horn with outer horns surrounding it, said horns being connected to said support and each comprising a tube portion and a mouth, said mouths all facing the same direction, said tube portions being 40 of different lengths and the mouths of the outer horns being arranged vertically in pairs one on each side of the central horn.
3. A sound device comprising a base having a sound responsive element therein, a central horn with outer horns surrounding it, said horns each comprising a tube portion and a mouth, the central horn rising from said base, said outer horns branching out from the tube portion of said central 50 horn, around the entire periphery thereof, said tube portions being of different lengths and the mouths of the outer horns being arranged vertically in pairs one on each side of the central horn. 55
4. A musical instrument comprising a base having a sound responsive element therein, a central horn with outer horns surrounding it, said horns each comprising a tube portion and a mouth, the central horn rising from said base, said outer horns branching out from the tube portion of said central horn, around the entire periphery thereof, said mouths all facing the same direction, said tube portions being of different 60 lengths and the mouths of the outer horns being arranged vertically in pairs one on each side of the central horn. 65

MILLER REESE HUTCHISON.
